UNITED STATES PATENT OFFICE

HARRY J. PERSON, OF LANSING, MICHIGAN, ASSIGNOR TO HARRY J. PERSON & SON INCORPORATED, OF LANSING, MICHIGAN, A CORPORATION OF MICHIGAN

MAUSOLEUM CONSTRUCTION

Application filed December 8, 1927. Serial No. 238,492.

This invention relates to an above-the-ground depository for human bodies, or a structure in the nature of what is commonly termed a mausoleum. An object of the invention is to provide an arrangement whereby the capacity of the structure may be readily increased from time to time to any desired extent and whereby the supporting walls of the entire structure are formed of 10 separate and distinct units with each unit designed to receive and hold a human body. A further object is to give to such structure the appearance of a beautiful building by spacing apart these walls of vertical rows of 15 units, to provide corridors extending from end to end of the structure and supporting upon these built-up walls a roof structure for such corridors with ornamental end structures or facades for covering and 20 sealing the wall ends and providing for entrances to the corridors with doors or gates for these entrances. A further object is to provide an arrangement whereby the end structure or facade is so connected and positioned relative to the built-up walls, that the facade may be removed and units added to 25 the walls as desired, and to provide a structure for the purpose which is substantially indestructible and in which each unit forms 30 a sealed moisture proof crypt or vault facing upon a corridor. It is also an object to provide an arrangement whereby the structure may be readily increased in width to any desired extent as well as any length, 35 for the purpose of symmetry, additional walls comprising a plurality of superposed units being placed with the rear ends of the units spaced from the rear ends of the units of an adjacent wall or walls and with narrow 40 passages between the rear faces of these adjacent walls, which passages are adapted for ventilation and inspection, the roof structure being extended over these passages and providing drain gutters. Further objects are 45 to provide certain other new and useful features in the construction and arrangement, all as hereinafter more fully set forth.

With the above and other ends in view, the invention consists in the matters herein- 50 after set forth and more particularly pointed

out in the appended claims, reference being had to the accompanying drawings in which

Figure 1 is an outline of a structure embodying supporting walls formed of a plurality of units which are shown in cross section, said structure being illustrative of an embodiment of the present invention; 55

Fig. 2 is a transverse vertical section of the structure;

Fig. 3 is a perspective detail of one of the 60 crypts or vaults forming one of the units of the supporting walls;

Fig. 4 is a longitudinal section of an end portion of the structure taken on a central vertical plane of one of the corridors; 65

Fig. 5 is a front end elevation of the end structure or facade of the building;

Fig. 6 is a detail showing a front end elevation of a plurality of units in place and with portions broken away and in section 70 to more clearly disclose the construction;

Fig. 7 is an enlarged horizontal sectional view of a portion of Fig. 6, and

Fig. 8 is a perspective detail of a member 75 for holding the adjacent ends of facing strips for covering the joints between adjacent units.

In the building of a structure of this character, a foundation 1 of suitable construction is first laid and this foundation may be of 80 any desired extent in area to take care of the needs of the structure as said structure is built up thereon, and this structure or building may at first comprise a single pair of opposed walls built up of the desired number of superposed units, each unit indicated as a whole by the numeral 2 comprising a rectangular box-like structure formed of any suitable moisture resisting impervious material, preferably concrete or the like which may be molded 85 into the desired form and hollow with an open end. This unit is preferably of a size to receive a single coffin containing a human body and after the body has been placed within the unit, said unit is sealed up air tight by placing in the open end of the unit, a closure 90 3 or slab adapted to fit the end of the unit and preferably beveled outwardly along its edges to receive a suitable packing material 4 to form an air tight joint. 95

The supporting walls of the structure are formed by placing these units 2 one upon another in vertical rows with the front ends of the units which are closed by the slabs 3, facing toward the front ends of a similar wall formed of similar units, which walls are spaced apart to form a corridor 5 between these walls.

As the units are set in place one upon the other, they are preferably covered with an exterior coating of any suitable material which will render each unit impervious to dampness and make the same air tight. The walls of these units are of considerable thickness and may be reinforced if found desirable to add strength thereto, thus giving to each unit a considerable weight, preferably running into thousands of pounds so that the possibility of cracking or crushing any unit is precluded by the superposing of these units or due to any settling of the foundation or movement of the earth's surface in case of an earthquake or the like. All of the supporting walls of the entire structure are therefore built up of these very heavy permanent units which are constructed of a material to withstand the ravages of time and the elements, and by spacing adjacent walls a suitable distance apart, a corridor or corridors are formed providing access to the front ends of the several units which face upon these corridors. As these walls are formed entirely of separate and distinct units which are separately constructed and kept in stock ready for use, such units may be added to the walls of the structure from time to time to increase the capacity of the structure and therefore a structure of small capacity may be first erected and then added to as required, by simply placing other vertical rows of units in place at the ends of the walls. When the structure having but one corridor has been extended to the desired length, another or other walls may be added alongside the first structure and upon the same foundation, thus increasing the width of the structure for the purpose of symmetry. The addition to the structure will comprise a pair of walls with a corridor between the front faces of those walls and preferably the rear face of the wall adjacent the original part of the structure will be spaced from the rear face of the adjacent wall of that structure, providing a narrow passage 6. The structure may therefore be added to indefinitely, providing a series of longitudinal supporting walls formed of vertical rows of superposed units with longitudinal corridors between the pairs of walls, and narrow passages between the rear faces of adjacent walls.

When the supporting walls have been built up to the desired height, the uppermost unit placed thereon will have an upper wall 7 which is tapered in thickness from the front to the rear end of the unit thus providing an

inclined upper surface for each supporting wall. A roof structure for the corridor 5 between adjacent supporting walls is formed by supporting upon the upper units of these walls a concrete slab, or other suitable roof member 8 with its ends resting within grooves or notches 9 formed in the front ends of the upper units 2 of the supporting walls, and this roof or slab 8 is also formed with inclined upper surfaces corresponding to the incline of the upper surfaces of the upper units 2 so that the exterior surface of the roof portion of the structure will have a slight inclination in each direction laterally from the longitudinal vertical central plane of the corridor to provide a pitch to the roof. A metal roof covering 10 is laid upon this surface and this covering is preferably formed of sheet bronze which is not affected by the elements and will provide a substantially indestructible roof for the structure. The outer or rear face of the supporting wall which forms one of the exposed sides of the structure, is preferably covered by an extension of the sheet metal 10 downwardly from the roof over this outer face of the side wall, as indicated at 11, and for appearance sake, a comparatively thin ornamental side wall 12 may be provided for the exposed side of the structure, this wall being added to as the supporting walls are increased in length through the addition of units 2.

Further, for appearance sake an ornamental front wall or facade 13 of any desired construction may be provided to cover and conceal the front ends of the supporting walls and to also close the ends of the passages 6, such face structure or facade being given the desired ornamental appearance externally, by casting the same in solid concrete sections or otherwise building it up to provide a very solid permanent structure with doorways 14 at the ends of the several corridors 5 and ornamental entrances and approaches to these doorways. This facade may, if found desirable, be formed of bronze to give permanency and a very rich ornamental appearance, the bronze facade corresponding to the bronze covering for the roof and enhancing the general richness in the appearance of the building. A similar end structure or facade is provided for the opposite end of the structure to also cover the ends of the supporting walls at that end of the building, but preferably one or both of these facades are so set and connected to the ends of the supporting wall that they may be moved and permit of placing of additional vertical rows of units at the ends of the supporting walls to increase the capacity of the structure.

Where a second pair of supporting walls formed of separate units is placed in parallelism with other pairs, with the passages 6 therebetween, the roof covering 10 is extended across these passages and is preferably de-

pressed along the passages, forming gutters 15 for carrying off the water draining from the adjacent roofs. The end structures or facades close the ends of the passages 6 and these passages may be provided with suitable ventilating openings (not shown) to give ventilation, and these passages may be entered for the purpose of examining the adjacent walls to see that each unit forming 10 these walls is in perfect condition.

The several units or crypts 2 are preferably set in place in the supporting walls prior to the depositing of a human body therein and after such deposit the slabs 3 for 15 closing their open ends are set in place and the end permanently sealed. After being so sealed, a sheet 16 of bronze or other suitable metal is applied over the corridor end of the unit or this plate may be applied to the slab 20 prior to the slab being set in place, the plate being then secured to the slab by securing a name plate 17 thereon with suitable anchor pins 18 passing through the plates and embedded in the slab. Where the face plate 16 25 is applied after the slab is set in place, the anchors 18 may be embedded in the slab when the slab is molded with the outer ends of the anchors projecting therefrom and then when the plates 16 and 17 are applied nuts or heads 30 19 are applied to the outer ends of the anchors to hold the plates in place. To close the narrow cracks or crevices between the corridor ends of the several units or crypts, moldings 20 are applied thereover, these 35 moldings being also preferably formed of bronze, and they are held in place at the four end corners of each crypt by means of an ornamental rosette or button 21 which engages over the ends of the four adjacent 40 moldings, and this button is held in place by a bolt 22 passing through the center of the rosette and into any suitable anchoring means located within the crevices between the units.

The side walls of each of the corridors 5 are thus given a very ornamental appearance and each crypt is provided with a permanent name plate which further adds to the decoration of the walls. The exterior of the structure may be given as an elaborate decorative 50 appearance as desired by the construction and designing of the end structures or facades and by making the entire structure from non-corrosive permanent material such as concrete 55 and bronze and forming the entire supporting walls of the building from units of very heavy solid construction, the structure is made practically indestructible, and by making the several crypts water proof and then 60 sealing the same, the structure becomes a resting place for the dead which is as permanent as the ancient tombs.

Having thus fully described my invention what I claim is:—

65 1. A structure including spaced apart

walls formed entirely of separate hollow units for the reception of human bodies, said walls forming side walls extending from end to end of the structure and a corridor therebetween, the upper surface of said upper units being inclined laterally of each wall, a roof member covering said corridor and supported directly upon the upper units of said walls, and a facade structure adjacent to and supported independently of the ends of said walls formed by said hollow units and provided with an entrance to said corridor.

2. A structure including pairs of spaced apart longitudinally extending parallel walls with the adjacent walls of each pair spaced apart to form narrow passages between the pairs of walls, the spaces between the pairs of walls forming corridors extending throughout the length of the structure, all of said walls being formed entirely of separate superposed hollow units for the reception of human bodies with an opening in the end of each unit opening into said corridors, the rear closed ends of the units forming the walls of said passages, a roof structure for each of said corridors and supported directly upon the two walls forming the corridor, and end facade structures adjacent the ends of said walls formed by said hollow units and supported independently of said walls to conceal the ends thereof and close the ends of said passages, said facade structure being provided with entrances for said corridors.

3. A structure as characterized in claim 2, and including in combination a metal face plate for the corridor end of each hollow unit to form a finish for the walls of said corridors.

4. A structure including a foundation, a plurality of spaced apart walls formed entirely of a plurality of separate hollow units for the reception of human bodies, said units being set upon said foundation and arranged in said walls, one upon another throughout the entire height of the walls, said walls forming between them corridors and passages extending from end to end of said walls, the upper units of said walls being provided with upper sides inclined downwardly longitudinally of the units toward said passages, slabs supported at their edges directly upon the upper units of the walls and forming roofs for said corridors, gutters covering the passages and supported upon the walls forming said passages, side and end facade structures supported upon said foundation adjacent to and independently of said walls and covering the ends and a side thereof, said end facades forming closures for the ends of said passages and provided with entrances for said corridors.

In testimony whereof I affix my signature.
